UNITED STATES PATENT OFFICE.

WARNER T. TABB, OF NEW YORK, N. Y., ASSIGNEE TO THE SAFETY CAR HEATING & LIGHTING COMPANY, A CORPORATION OF NEW JERSEY.

ART AND APPARATUS FOR LIGHTING.

Application filed May 5, 1917. Serial No. 166,674.

To all whom it may concern:

Be it known that I, WARNER T. TABB, a citizen of the United States, and a resident of the borough of Manhattan, city of New York, county of New York, and State of New York, have invented an Improvement in the Art and Apparatus for Lighting, of which the following is a specification.

This invention relates to an art and apparatus for lighting, and in regard to certain more specific features thereof, for the lighting of buoys and the like. One of the objects thereof is to provide practical means of simple construction for generating a source of light. Another object is to provide means of the above type of reliable action and peculiarly adapted for use in isolated relations, such as lighting buoys. Another object is to provide means of the above type which shall be durable and automatic in action and will not require attention for long periods of time. Other objects are to provide a simple and practical art to generate light and more particularly in isolated relations. Other objects will be in part obvious and in part pointed out hereinafter.

The invention accordingly consists in the features of construction, combinations of elements, arrangement of parts and in the several steps and relation of such steps, all as will be hereinafter illustratively described, and the scope of the application of which will be pointed out in the following claims.

The accompanying drawing is a diagrammatic sectional elevation of one of various possible embodiments of this invention.

Referring now to this drawing in detail, there is shown at 1 the body or float portion of a buoy which is preferably formed of sheet metal and contains in the present instance a combustible gas confined under pressure. This buoy is so proportioned as not only to afford the desired floating capacity but to maintain in an upright position the light support 2 having at its upper end a suitable annular lens 3.

Mounted upon the upper surface of the float or container 1 is a casing 4 in which are mounted the controlling and operating mechanisms to be hereinafter described. The gas contained under pressure in casing 1 passes through port 5 into the pressure regulator and reducer 13 by which it is fed

at the desired uniform pressure to the casing 4. The regulating device may be of any suitable well known form, the details of construction not being here shown as they form in themselves no part of the present invention. From the pressure regulating device 13, the gas passes through port 5 and passage 6 to port 7 and thence into casing 4. The flow through passage 6 may be controlled as by the adjustable needle valve 8. From casing 4 the gas passes through a port 9 and passage 10 controlled in like manner by a needle valve 11. From this passage a tube 12 leads as indicated by the arrows to the Bunsen burner 14 mounted on a suitable base 13' on the casing 4.

The air for combustion in the Bunsen burner is fed inwardly through a conduit 15 extending through the walls of the light support 2.

Positioned in the casing 4 is a diaphragm 16 urged downwardly as by the coil spring 17 and subjected on its lower side to the upward pressure of the accumulating gas. Extending downwardly from this diaphragm is a rod 18 provided with pins 19 and 20 adapted alternatively to engage a narrow thin flat spring 21. This spring is snapped into slightly bowed position in grooves in abutments 22 and 23 formed in the walls of the casing, and in the position shown in full lines, is bowed downwardly. When, however, the diaphragm is raised by the accumulated gas to such an extent that the pin 20 presses firmly against the lower surface of this spring 21, it will be snapped into the upwardly bowed position indicated in dotted lines. It is to be understood that this spring is narrow and does not prevent the entry of gas into the upper portion of the casing.

Pivotedly mounted at 24 on the abutment 25 is a lever 26 provided with a pair of pins 27 closely engaging the spring 21. The lower end of this lever is formed into a valve 28 mounted above the open end of the passage 6. In the position shown, this valve permits free entry of gas into the casing, but upon the diaphragm 16 being raised to a predetermined extent by the accumulated gas and the spring 21 being snapped upwardly as above described, the lever 26 will be rocked to bring this valve against its seat. The supply of gas is thus cut off and is not re-

newed until sufficient gas has escaped through the tube 12 to allow the spring 17 to force the diaphragm downwardly and snap the spring 21 into its full line position.

5 In one wall of the casing 4 in suitable insulation 29 are a pair of conductors 30 and 31. These conductors are connected with thin flat springs 32 and 33 which tend to spring upwardly and bring their free ends, 10 indicated at 34, into engagement with the conductors 35 and 36. These springs with the parts in the position shown, however, are held downwardly by the insulating pins 37 on the lever 26 in such manner that the 15 spring 32 is in electrical connection with the conductor 36 and the spring 33 in like connection with a conductor 38.

Connected across the conductors 30 and 31 is a storage battery 39 and it is to be noted 20 that by the intermittent action of the diaphragm 16 with associated parts, the terminals of this battery are alternatively connected with conductors 35 and 36 or with conductors 36 and 38.

25 Positioned in the range of greatest heat from the Bunsen burner 14 are a plurality of thermo-electric couples 39'. These couples, which may be of any desired number, are formed in the well known way by 30 the junction of two dissimilar metals, and it is to be understood that by the term "thermo-electric couple" is meant a device comprising a junction of dissimilar metals or materials adapted to cause the flow of electric current upon being connected in a circuit and subjected at their junction to heat.

Assuming now that each of these couples comprises a member 40 of one metal and a member 41 of dissimilar metal, the couples 40 are connected in series as shown, and their unheated ends are positioned in the cold air inlet of the Bunsen burner as shown, in order to give a greater difference of temperature and a correspondingly enhanced thermo-electric effect.

From one terminal of this thermo-electric pile a conductor 42 is led directly to the conductor 36. From the remaining terminal a conductor 43 is led to the conductor 35, and a branch conductor 44 leads through an incandescent lamp 45 preferably positioned substantially at the optical center of the annular prismatic lens 3. Continuing from this lamp, a conductor 46 is led to the conductor or contact 38.

Considering now the action of this apparatus, the burner 14 is continuously supplied with combustible gas under a reduced uniform pressure from the container, although 60 if desired, this may be intermittently cut down by a clockwork-controlled valve or other means. The heat of this burner is utilized to act on the thermo-electric pile above described, this action being enhanced by the 65 automatic cooling of the opposite terminals

of each couple. In this manner, a thermo-electric current is generated, and it may be noted that by the term "thermo-electric current" is meant any electric current generated by means of a thermo-electric pile. With 70 the parts in the position shown, this current is led through the lamp 45 in series with the storage battery 39 and the polarity of the parts is such that both the thermo-electric pile and the battery tend to supply the lamp 75 with current. The current generated in the pile is thus led directly through the lamp. When the springs 32 and 33, however, are permitted to snap upwardly into connection with the conductors 35 and 36, the lamp circuit is broken and the battery, which is of lower voltage than the thermo-electric pile, 80 is stored by the continuing current of the latter. This current generated by the pile, is thus not led directly through the lamp 85 but indirectly by means of the storage battery. When the parts reassume the position indicated in full lines, the battery and pile in series feed the lamp.

By the above action, the desired intermittent 90 flashing of the lamp is gained and yet current generated by the pile is economically used, as even during the dark period of the lamp it is stored in the battery 39. By suitable adjustment of the parts such as the needle valve 8, a suitable regulation of this 95 period may be gained, and by proper positioning of the pins 19 and 20, the desired relation of duration of light and dark periods is achieved. It will also be seen that the 100 entire apparatus is thoroughly automatic in action and the parts of such simple construction and reliable operation that the apparatus may be depended upon for continuous action throughout an indefinite length 105 of time.

It will thus be seen that there is provided apparatus in which certain of the objects of this invention are achieved and that the same is well adapted to meet the hardest requirements of practical use. It will also be seen that the remaining objects are fulfilled in the above described art of lighting which as to its broader features might well be carried on with different types of apparatus.

As various possible embodiments might be made of the mechanical features of this invention and as various changes might be made in the precise method of carrying on the above art, it is to be understood that all matter herein described or shown in the accompanying drawing is to be interpreted as illustrative and not in a limiting sense.

I claim as my invention:

1. In apparatus of the class described, in combination, a vessel for storing a fluid under pressure, an electric switch, a regulating valve connected to said vessel through which said gas may escape, said valve having a diaphragm subjected by said gas to a 123 130

slowly progressive movement between two predetermined limits, and means operative by said diaphragm at the end of its movement for operating said switch.

5. 2. In buoy construction, in combination, a float having gas stored therein under pressure, a thermo-electric couple supported by said float, means adapted to burn gas from said float adjacent said couple, a lamp supported by said float, means adapted to lead current generated by said couple through said lamp, and means operated by said gas on its passage to said gas-burning means for intermittently interrupting the current to said lamp.

10. 3. In buoy construction, in combination, a floating buoy, an electric lamp exposed from said buoy, a storage battery, means for containing a fluid under pressure, means adapted to lead current from said battery through said lamp, and means operated by said fluid for intermittently interrupting the flow of current through said lamp, said battery and said several means being mounted on and floated by said buoy.

15. 4. In buoy construction, in combination, a float having gas stored therein under pressure, a thermo-electric couple supported by said float, means adapted to burn gas from said float adjacent said couple, a storage battery supported by said float, a lamp supported by said float, and means adapted alternatively to connect said couple, battery and lamp in series and to connect said battery and couple in series excluding said lamp, said means being operated by said gas.

20. 5. In combination, means adapted to store gas under pressure, an electric switch, and means actuated by said gas as it escapes from said storing means adapted intermittently to operate said switch.

25. 6. In combination, means adapted to store gas under pressure, an electric switch, means actuated by said gas as it escapes from said storing means adapted intermittently to operate said switch, means adapted to burn said gas, a thermo-electric couple adjacent said combustion, a storage battery, and connections between said couple and said battery controlled by said switch.

30. 7. In apparatus of the class described, in combination, means adapted to store gas under pressure, a thermo-electric couple, means adapted to burn gas from said storage means and adjacent said couple, an electric lamp, a switch adapted to connect said lamp to said couple, and means operated by said gas as it passes from said storing means to said gas-burning means for intermittently operating said switch.

35. 8. In apparatus of the class described, in combination, means adapted to store gas under pressure, a thermo-electric couple, means adapted to burn gas from said storage means and adjacent said couple, an elec-

tric lamp, a storage battery, a switch adapted in one position to permit said couple to supply current to said battery and in another position to permit said battery to supply current to said lamp, and means actuated by said gas as it escapes from said storing means adapted alternately to place said switch in said two positions.

40. 9. In apparatus of the class described, in combination, means adapted to store gas under pressure, a thermo-electric couple, means adapted to burn gas from said storage means and adjacent said couple, an electric lamp, a storage battery, a switch adapted in one position to connect said couple, said battery and said lamp in series and in another position to connect said couple and said battery in parallel, and means actuated by said gas as it escapes from said storing means adapted to alternately place said switch in said two positions.

45. 10. In apparatus of the class described, in combination, means adapted to store gas under pressure, a thermo-electric couple, means adapted to burn gas from said storage means and adjacent said couple, an electric lamp, a regulating valve having a diaphragm for governing the pressure of the gas supplied to said gas-burning means, said diaphragm being subjected by said gas as it escapes to movement between two predetermined limits, a switch adapted to connect said lamp to said couple, and connections between said diaphragm and said switch whereby the latter is intermittently operated.

50. 11. In apparatus of the class described, in combination, means adapted to store gas under pressure, a thermo-electric couple, means adapted to burn gas from said storage means and adjacent said couple, a chamber having a diaphragm, said chamber being interposed between said burning means and said storage means and connected to the latter through a valve, an electric lamp, a switch adapted to connect said lamp to said couple, means connecting said diaphragm to said valve whereby said valve controls the flow intermittently of gas to said chamber to extend said diaphragm intermittently, and means for operating said switch from said diaphragm.

55. 12. In apparatus of the class described, in combination, means adapted to store gas under pressure, an electric switch, a chamber having a diaphragm, said chamber being connected to said storage means through a valve and having means to permit gas to escape from said chamber, means connecting said diaphragm to said valve whereby said valve is closed upon said diaphragm being extended and opened upon said diaphragm returning to normal, and means for operating said switch from said diaphragm.

13. In apparatus of the class described, in combination, means adapted to store gas under pressure, a movable switch member, a chamber having a diaphragm capable of movement between two predetermined limits, said chamber being connected to said storage means through a valve and having means to permit gas to escape therefrom, means connecting said diaphragm to said valve whereby said valve is closed upon said diaphragm being extended and opened upon said diaphragm returning to normal, and connections between said diaphragm and said switch member adapted to give said switch member a rapid movement as said diaphragm approaches either of said limits of movement.
14. In apparatus of the class described, in combination, means adapted to store gas

under pressure, a movable switch member, a chamber having a diaphragm capable of movement between two predetermined limits, said chamber being connected to said storage means through a valve and having means to permit gas to escape therefrom, a spring member connected to said diaphragm to be stressed thereby and adapted to partake of a rapid movement upon a predetermined stressing movement of said diaphragm, and means connecting said valve and said switch member to said spring member to be rapidly operated thereby.

In testimony whereof, I have signed my name to this specification this 2nd day of May, 1917.

WARNER T. TABB.
